ARTIS CHESTER BRYAN, OF SYRACUSE, NEW YORK

OIL BURNING HEATER

Application filed March 14, 1928. Serial No. 261,537.

This invention relates to an oil-burning heater adapted to be used more particularly in connection with furnaces and other house heaters which have been previously installed 5 for burning coal and other solid fuels, but obviously may be used in connection with heaters specially built and coordinated with this particular type of burner for economy in space and maximum heating efficiency.

10 In apparatus of this character the oil tank or other container for the source of oil supply is preferably placed below the level of the burner in the furnace and is usually imbedded in the ground at the exterior of the 15 building for safety purposes and also for convenience in refilling and it, therefore, becomes necessary to pipe the tank to a supplemental but relatively small reservoir or tank into which relatively small quantities 20 of the oil may be periodically or intermittently drawn, preferably by suction, from which the oil may be supplied as needed to the burner and the supply automatically controlled by suitable devices, hereinafter de- 25 scribed.

Furthermore, it is preferable to employ the usual electric house current for ignition purposes through the medium of suitable electrodes or ignition terminals having special relation to the fuel discharge end or nozzle of the burner and incidentally involving the use of a suitable transformer for producing the desired ignition spark at the electrode terminals.

35 The heaters are usually equipped with suitable fuel inlet openings and doors or similar closures therefor and one of the main objects of the present invention is to mount the fuel mixing and ignition elements 40 together with the supplemental oil reservoir and transformer directly upon the outer face of the door to move therewith as the door is opened and closed.

Another object is to provide the supplemental reservoir with a vacuum chamber operatively connected to a suitable suction device and to the source of oil supply whereby a limited quantity of oil may be drawn thereinto from said source and to provide the 50 vacuum chamber with float-controlled valves

whereby the operation of the float by the inflowing oil will automatically cut off the supply when a pre-determined quantity has been drawn into the vacuum chamber and at the same time automatically break the force 55 of the vacuum by opening a portion of the suction passage to the atmosphere.

A further object is to provide the vacuum tank with means for automatically discharging the oil therefrom into an inclosing housing immediately upon the breaking of the vacuum in said tank.

Another object is to connect the burner to the supplemental housing of the vacuum tank by means of a suitable conduit or pipe 60 and also to introduce air into the burner under pressure in such manner as to draw the oil from the supplemental housing into the burner to establish a thorough mixture with the oil and to enable said mixture to be discharged through the nozzle of the burner for ignition by the electrodes of the burner as long as the mixture continues to flow during which time the float in the vacuum tank will return by its own weight to open the fuel 70 inlet valve and to close the vacuum vent for replenishing the oil in the supplemental tank 75 as fast as it is withdrawn therefrom.

Another object is to provide the supplemental tank with a safety float and valve 80 operated thereby for controlling an additional vacuum vent so that in case an excessive amount of oil is drawn into the vacuum chamber by suction the additional float will automatically open the vent valve to break 85 the vacuum and thereby prevent further accumulation of oil in the supplemental tank.

Another object is to provide the burner with heat-controlled means for regulating the quantity of combustible mixture discharged 90 through the nozzle.

A further object is to enable the burner to be adjusted to different angles as may be required to direct the flame to the proper position within the combustion chamber of the 95 furnace according to the height of the fuel inlet door upon which the burner is mounted.

Other objects and uses relating to specific parts of the apparatus will be brought out in the following description. 100

In the drawings:—

Figure 1 is a more or less diagrammatic view of a furnace equipped with my improved burner together with a motor-driven pump and pipe connections between the pump and vacuum tank showing also the various electrical controls for the pump motor.

Figure 2 is an enlarged vertical sectional view through the front portion of the furnace showing the manner of mounting the burner and associated parts upon the furnace door and also the construction of the fire baffle within the combustion chamber and against which the flame from the burner is directed for incandescent purposes.

Figure 3 is a front face view of the baffle shown in Figure 2.

Figure 4 is an enlarged top plan of the detached vacuum tank.

Figure 5 is a detail sectional view taken on line 5—5, Figure 4.

Figures 6 and 7 are vertical sectional views of the vacuum tank taken on lines 6—6 and 7—7, Figure 4.

Figure 8 is a detail sectional view of the float-controlled oil valve shown in Figure 6 except that the valve is closed.

Figure 9 is a sectional view taken in the plane of line 9—9, Figure 10.

Figure 10 is a horizontal sectional view, partly in top plan, taken in the plane of line 10—10, Figure 9.

Figure 11 is a detail sectional view, partly in elevation of the vacuum regulating device.

Figure 12 is a sectional view taken in the plane of line 12—12, Figure 10.

The mechanism forming the subject matter of this application may be used in connection with any heater as —A— having a combustion chamber —A'— and a fuel inlet opening —a— leading thereto through the front side of the furnace some distance above the grate —B—, the fuel inlet opening being provided with a suitable door or closure —1— upon which certain mechanisms of the invention are mounted for supplying and igniting the necessary fuel mixture and burning the same within the combustion chamber —A'—.

The heat developed in the combustion chamber may be used for heating air, water or converting the water into steam and in order that the heat produced in the combustion chamber may be retained as long as possible and also for increasing the intensity of the heat transferred to the distributing system a suitable baffle —C— is supported upon the grate —B— directly in the path of the flame from the burner, said baffle being preferably made of heat refracting material, such as fire brick, capable of incandescence under a sufficient degree of heat.

The mechanisms which are carried by the door —1— are preferably mounted upon a separate plate —2— which is secured by bolts —3— to the outer face of the door and is pro-

vided with an extension —4— projecting through an opening —5— in the door and into the fuel inlet opening —a—.

The burner comprises a frame —6— having its opposite ends provided with horizontally extending trunnions —7— journaled in split bearings —8—, the split sides of which are provided with clamping bolts —9— for attaching the bearing members —8— to the inner wall of the extension —4— of the plate —2— and also for tightening and loosening the split bearings —8— upon and from the trunnions —7—.

The frame —6— is, therefore, journaled for rocking movement upon and within the extension —4— through the medium of the split bearings —8— which, when tightened by their respective clamping bolts —9— serve to frictionally hold the frame —6— and parts carried thereby in different positions of adjustment for a purpose hereinafter explained.

The central portion of the frame —6— is provided with a forwardly and rearwardly extending tubular head or barrel —10— having a lengthwise bore —11— extending therethrough from end to end and branch passages —12— and —13— leading from the underside of the head to the bore in axially spaced relation and preferably at an angle to the axis of the bore inclined forwardly and inwardly for receiving air under pressure and fuel oil respectively in a manner hereinafter more fully described.

The branch passage —12— is located more nearly midway between the opposite ends of the bore and is connected by piping —14— to the pressure side of a motor-driven pump —15—, as shown more or less diagrammatically in Figure 1, for supplying air under pressure to the burner to produce the necessary mixture with the fuel oil for combustion.

The oil passage —13— is connected by piping —16— to an oil reservoir —17— of a vacuum tank —18— for supplying the necessary fuel oil to the mixing chamber as —19— of the burner to which the oil passage —13— is directly connected as shown in Figure 9.

The portion of the lengthwise opening —11— in the head —10— between the passages —12— and —13— is threaded at —20— to be engaged by the threaded portion of a tubular valve stem —21— which extends through the major portion of said bore or opening —11— from the outer end across the passage —12— and mainly across the passage —13— so that its inner end may terminate a relatively short distance from the inner end of the head —10— or adjacent the inner side of the adjacent end of the oil passage —13—.

The intermediate portion of the valve stem —21— and adjacent portion of the opening —11— are spaced apart to form an annular chamber —22— registering with the air passage —12— and communicating with the in-

terior of the valve stem —21— through radial openings —23— in said stem to allow air under pressure to pass from the passage —12— into the interior lengthwise passage —24— of said stem.

The inner end of the tubular stem —21— is extended slightly beyond the adjacent end of the oil opening —13— and is reduced in diameter to form a part of the mixing chamber —19— which communicates with the passage —13—.

The reduced inner end of the valve stem —21— is provided with a central restricted opening —24'— forming a continuation of the passage —24— to allow the air under pressure to pass first into the mixing chamber across the adjacent end of the oil passage —13— and thence into the combustion chamber —A'—, it being understood that the restricted passage —24— serves to increase the velocity and pressure of the inflowing air.

This current of air passing across the adjacent end of the passage —13— acts upon the principle of an ejector for creating sufficient suction through the mixing chamber to draw the oil from the reservoir —17— through the connecting piping —16— into the mixing chamber where it is thoroughly agitated and mixed with the air and projected by the air pressure through a suitable nozzle —25—.

This nozzle —25— is provided with a reduced threaded portion engaging internal threads —26— on the inner end of the head —10— so that it may be adjusted or set to different positions relatively to the inner end of the valve stem —21—.

The outer end of the valve stem is provided with a hand wheel —27— by which it may be turned for axial adjustment in the screw threaded portion —20— to bring its inner end into more or less close proximity to the adjacent end of the nozzle as may be required for regulating the amount of oil drawn into the mixing chamber —19— and delivered through the nozzle —25— into the combustion chamber of the heater.

The valve stem —21— may be held in any position of adjustment by means of a set screw —28— mounted on the outer end of the head —10— and adapted to engage the periphery of the hand wheel —27—, as shown in Figure 9.

Electric ignition

A pair of insulating sleeves —29— are mounted upon the frame —6— at opposite sides of and parallel with the head —10— for receiving and supporting a pair of electrodes —30— in transversely spaced relation.

These electrodes —30— are extended through and beyond the opposite ends of their respective insulating sleeves —29— and are shouldered against the inner ends of said sleeves, the outer ends of said electrodes being provided with clamping nuts —31—

engaging the adjacent ends of their respective insulating sleeves —29— for firmly holding the electrodes in operative position.

The inner ends of the electrodes —30— are deflected toward each other to form spark terminals —32— which are spaced a relatively short distance apart to form an intervening spark gap —33— adapted to be varied at will either by bending the terminals toward or from each other or by turning them about their respective axes.

The outer ends of the electrodes —30— are connected by flexible leads or cables —34— to a suitable transformer —35— which, in turn, is connected by wires —36— to a suitable source of electric energy for supplying the necessary current to the electrodes —30— for ignition purposes.

The transformer —35— and vacuum tank —18— are bolted or otherwise secured to the plate —2— to open and close with the door and while the burner is also mounted upon the same plate, it, together with the electrodes is tiltable about the axis of trunnions —8— to direct the flame from the burner into the combustion chamber at different levels according to the height of the fuel inlet door —1— or, rather according to the relative heights of the baffle —C— and fuel inlet opening.

It will be noted upon reference to Figures 2 and 9 that the electrodes —30— are disposed in a plane at an angle to the axis of the tubular stem —21— so that the inner terminal ends of said electrodes may incline inwardly and upwardly upon the axis of the tubular stem and, therefore, out of the path of travel of the combustible mixture as it is projected into the combustion chamber from the nozzle —25—, the object of which is to keep the terminal ends of the electrodes from being fouled by accumulations of the oil or combustible mixture.

The vacuum tank —18— is provided with a vacuum chamber —37— having an oil inlet in which a partial vacuum is intermittently maintained for drawing oil thereinto and for this purpose the top wall thereof is provided with a suction port —38— and an oil inlet port —39—, the suction port —38— being connected by conduits —40— to the suction side of the pump —15— while the oil intake port —39— is connected by pipes or conduits —41— to an oil supply tank —42— which is preferably imbedded in the ground at a level some distance below that of the burner.

The degree of vacuum maintained in the chamber —37— for drawing the oil from the main supply tank —42— depends somewhat upon the difference in levels of the supply tank and vacuum tank and is regulated by a vent tube —43— which is connected to the vacuum pipe —41— preferably adjacent the vacuum tank and is provided with an atmos-

phere port —44— normally closed by one or more ball valves —45— arranged to normally close the port —44— by their own weight, but adapted to be opened by suction from the 5 suction side of the pump —15— in case the vacuum in the chamber —37— exceeds a predetermined degree beyond that required to effect an up-flow of the oil from the supply tank —42— into the port —39— and thence 10 into the vacuum chamber.

This vent tube —43— is removable to permit the number of balls to be changed at will to coordinate the weight thereof with the degree of vacuum required.

15 The suction port —38— is controlled by a float-operated valve —46— having a downwardly extending stem —47— connected to one arm of a bell-crank lever —48— which is pivoted at —49— to a suitable bracket —50— 20 depending from the underside of the top wall of the vacuum chamber —37— as shown more clearly in Figures 6, 7 and 8.

The top wall of the vacuum chamber —37— is also provided with an atmosphere 25 port —51— controlled by a valve —52— having a downwardly extending stem —53— pivoted to one arm of a bell-crank lever —54— which is similar to the lever —48— and pivoted coaxial therewith by the same 30 pivotal pin —49—.

The other arms of the bell-crank levers —48— and —54— extend upwardly from their respective pivots —49— and are connected to each other by a transverse pin 35 —55— extending through a slot —56— in the weighted arm of an intermediate bell-crank-lever —57— which is pivotally mounted upon the same pin —49—, the slot —56— being concentric with the axis of said pivotal pin.

40 The crank arm of the weighted lever —57— is attached by a slot and pin connection —58— to the upper end of a downwardly projecting link —59— having its lower end connected 45 to the intermediate portion of a lever —60—.

This lever —60— is fulcrumed at one end upon a bracket —61— and has its other end connected to a float —62— which is movable vertically in the vacuum chamber —51— by 50 the rise and fall of the oil therein.

The levers —48— and —57— are arranged to open the suction controlling valve —46— and to close the vent valve —52— when the float —62— assumes its lowermost position 55 by the discharge of oil from the chamber —57—.

On the other hand, as the oil is drawn into the chamber —37— by the vacuum therein the float —62— will be gradually elevated to operate the weighted lever —57— from its normal position mainly at one side of the vertical plane of the pivot —49— until its weight is carried to the other side of said plane whereupon the automatic further movement of the 60 weighted member by its own weight will in-

stantly shift the bell-crank-levers —48— and —54— to close the valve —46— against the port —38— and to open valve —32— from the port —51— thereby simultaneously cutting off the oil supply at the port —38— and 70 venting the vacuum at the port —51— to the atmosphere to break the force of the vacuum and thereby to additionally stop the flow of oil into the chamber —37—.

The bottom of the vacuum chamber —37— is provided with an outlet —63— leading to an underlying screen pocket —64— and provided with a self-closing valve —65— which is held in its closed position by the force of the vacuum in the chamber —37— when the valve —46— is opened and the valve —52— is closed but immediately opens by the weight of the oil in the chamber —37— when the vacuum in the chamber —37— is broken as just explained thereby discharging the oil 85 from the chamber —37— in the reservoir —17— and allowing the float —62— to drop to its lowermost position for restoring the valves —46— and —52— to their starting positions for re-establishing the partial vacuum in the chamber —37— and incidentally closing the valve —65—.

In this manner a limited supply of oil is maintained in the reservoir —17— to be siphoned therefrom through the pipe —16— and into the burner by the passage of air through the valve stem —21— and nozzle —25—, as previously explained.

Safety vent

The top wall of the vacuum chamber —37— is provided with a safety vent port —66— controlled by a valve —67— having a depending stem —68— connected to the intermediate portion of a lever —69— which is pivoted at one end at —70— to the bracket —61— and has its lower end connected to a supplemental float —71— which is movable in the vacuum chamber —51— at one side of the vertical path of movement of the float 110 —62—, as shown in Figure 6.

The weight of the float —71— normally holds the valve —67— in its closed position, but, if for any reason the float —62— and parts operated thereby should fail to be operated by the inflowing oil in the chamber —37— the rise of said oil in said chamber to a predetermined level will operate the float —71— and valve —67— to open the vent port —66— to the atmosphere thereby breaking the force of vacuum in the chamber —37— and incidentally stopping the further flow of oil into said chamber until the cause of the operation of the safety float is removed.

One or more vertical guide ribs —72— are formed upon the interior walls of the vacuum chamber —37— between the floats —62— and —71— to guide them in their vertical movements without interfering with each other.

The plate —2— is provided with a sight 130

opening —73—therethrough from front to rear for inspection of the effects of combustion within the combustion chamber, said opening normally closed by a suitable gate 5 —74— through the medium of a weight —75—, the gate being free to open outwardly to relieve any internal compression within the combustion chamber as a result of abnormal explosion or combustion of gases 10 therein.

The pump —15— is operated by an electric motor —M— belted to a suitable pulley on the pump and adapted to receive current from the usual house line circuit —m— 15 through the medium of a temperature regulated motor switch —S—, preferably of the well-known Honeywell type, which is preferably mounted upon the supporting base for the motor —M— and pump —15—, as shown 20 in Figure 1.

That is, the circuit to the motor —M— is automatically opened and closed by the motor switch —S—, the operation of which is made dependent upon varying temperatures in or 25 adjacent the heater or in some one or another of the rooms of the building in which the heater is located so that when the temperature rises or falls above or below a predetermined degree in or adjacent the furnace or room the 30 pump operated motor will be stopped or started as the case may be, and incidentally stopping or starting the flow of fuel oil and air through the burner, said motor switch being also used to control the current through 35 the transformer —35—.

In Figure 1 of the drawings are shown, by dotted lines and somewhat diagrammatically, three types of temperature regulated means for controlling the operation of the 40 switch —S— comprising, in this instance, a combustion safety control or stackstat —X— of the Honeywell type B—9—*a* arranged within or adjacent the smoke stack —*a'*— of the heater, as shown by dotted lines in Figure 45 1.

An auxiliary temperature controlling device —Y— may be mounted in the heat-distributing chamber or adjacent side of the heater and commonly known as an auxiliary 50 control which may be either an aquastat, vaporstat or airtstat of any well-known make.

A thermostat —Z— may be placed at any suitable location within the building in which the heater is located and electrically connected 55 to the switch —S— to control the same and thereby to control the operation of the motor —M— as the temperature in the room rises and falls above and below a predetermined degree.

All of these automatic temperature operated devices —X—, —Y— and —Z— are 60 electrically connected to the switch —S— to act conjointly or independently in controlling the operation of the switch and thereby 65 controlling the operation of the pump which,

in turn, controls the supply of oil and air constituting the combustible mixture to the combustion chamber of the heater and not only increases the safety of the apparatus as a whole, but also conserves the current used 70 in the operation of the pump motor and resultant conservation of the current used in the transformer and consumption of oil in the combustion chamber of the heater.

The opening in the top wall of the chamber 75 —17— for receiving the pipe —16— is slightly larger than said pipe to provide an air-vent and thereby to facilitate the draft of oil from said chamber into the burner by the suction produced by the inflowing current of 80 air through said burner.

It will be noted upon reference to Figure 6 that the lower side of the ball —67— is flat and projects laterally beyond its supporting stem —68— so that when the ball valve 85 —67— is opened by the rise of the float —71— it will shift laterally by its own weight due to its inclination from a vertical so that as the oil recedes from the float —71— the lower surface of the ball valve —67— will engage 90 the upper face of its seat in the direction of the inclination of the stem —68— and thereby lock the float —71— in its elevated position as indicated by dotted lines in Figure 6 95 for the purpose previously explained.

The specific object in locating the oil passage —13— at the bottom or lower side of the mixing chamber —19— and nozzle —25—, Figure 9, is to assure the backflow of any oil, even the smallest amount into the chamber 100 —17— through the pipe —16— when the machine is shut down or its operation stopped thereby reducing the liability of carbonizing the passages —24'— and —25— and at the same time increasing the safety of the apparatus 105 against accidental explosion of the oil, particularly at the burner.

As previously stated, the ignition terminals —32— of the electrodes —30— are disposed in a plane slightly above the path of the inflowing combustible mixture but still in sufficiently close proximity to said path to cause the inflowing mixture to draw the spark thereto.

That is, the rapidity of the inflow of the explosive mixture slightly below the plane of the terminal and suction produced thereby causes the spark to be drawn into the path of travel of said mixture to secure complete combustion thereof and at the same time avoid accumulations of carbon on the terminals.

What I claim is:

1. In a heater having a combustion chamber and a fuel inlet opening leading thereto and provided with a door, an oil burner mounted on the door and provided with a fuel discharge nozzle and electrode ignition terminals projecting into said opening along 125 130

inwardly and downwardly inclined planes, the fuel-discharge nozzle being disposed at a greater angle from a horizontal plane than the electrode terminals, for discharging the fuel in a path below said terminals.

2. In an oil burning heater of the character described, a plate adapted to be secured to a part of the heater and provided with an opening therethrough for communication with the combustion chamber of said heater, a frame hingedly supported on the plate within said opening for vertical adjustment to different angles, a fuel delivery head mounted on the frame to tilt therewith, and electrodes mounted on the frame at opposite sides of the head and provided with ignition terminals some distance beyond and in a plane above the inner end of the head.

3. The combination with the fuel door of an oil-burning heater, of an oil-burner mounted on the door and provided with a fuel discharge nozzle and ignition electrodes, a vacuum tank mounted on the door for supplying fuel to the nozzle, and a transformer for the current to the electrodes mounted on said door, said burner having its electrodes disposed at opposite sides of and terminating in a plane above the discharge end of the fuel-nozzle.

30 4. The combination with the fuel-door of an oil-burning heater, of an oil-burner hinged to swing about a horizontal axis in an opening in said door and comprising a fuel-discharge nozzle, and ignition electrodes arranged at opposite sides of said nozzle and having their ignition terminals disposed in a plane above said nozzle.

5. An oil-burning unit comprising a plate adapted to be secured in the fuel opening of a heater and provided with an upright portion and a horizontal portion, a burner tiltably mounted in an opening in the upright portion of the plate and provided with a fuel-discharge nozzle and a pair of electrodes arranged at opposite sides of said nozzle and having their ignition terminals disposed in a plane above said nozzle, a fuel supply tank mounted on the horizontal portion and connected to said nozzle, and a transformer for the current to the electrodes mounted on said horizontal portion and connected to said electrodes.

6. In an oil-burning heater, a plate adapted to be secured in the fuel opening of the heater and provided with an opening therethrough leading to the fuel opening, journal bearings on opposite walls of the plate-opening, a frame having its opposite ends journaled in said bearings for vertical tilting movement, means for tightening and loosening the bearings upon and from the frame, a fuel nozzle on the frame, and a pair of electrodes mounted on the frame at opposite

sides of the nozzle and having ignition terminals disposed in a plane above said nozzle.

In witness whereof I have hereunto set my hand this 7th day of March, 1928.
